UNITED STATES PATENT OFFICE.

JOHN S. BANKRAT, OF HEMPSTEAD, NEW YORK.

PROPELLER.

Application filed February 10, 1927. Serial No. 167,232.

My invention relates to airplane or boat propellers and has a particular reference to propellers provided with internal passages for the fluid in which the propeller operates.

5 In ordinary propellers there is always a certain amount of vacuum formed at the rear portion of the propeller blades which vacuum interferes with the forward movement of the propeller and reduces its efficiency. In order to obviate this difficulty I provide my propeller with a hollow hub and internal passages through which the fluid is admitted under pressure inside of the blades from which it emerges through suitably located holes located at points where vacuum usually forms.

10 My invention is more fully described in the accompanying specification and drawing in which—

15 Fig. 1 is a sectional elevation of my propeller (showing portions only of the blades), Fig. 2 is a top view of same, Fig. 3 is a sectional elevation taken endwise, and Fig. 4 is a diagrammatic view illustrating action of my propeller.

20 My propeller comprises a hub 1 mounted on a motor shaft 2 and fastened with a nut 3 (or in any other suitable manner.) The front portion of the hub is made hollow being provided with a circular cavity 4. 25 Blades 5 are attached to the hub. These blades are made hollow inside with cavities 6 in communication with the cavity 4. A plurality of small holes 7 are provided in the rear portion of the blades at points where the undesirable vacuum is likely to be formed (Fig. 4).

25 The hub has reinforcing straight webs 8 between the blades and spiral guiding webs 9 directing the air to the inner portions of the blades as shown with arrows 10.

30 The total area of the holes 7 is smaller than the cross-sectional area of the hub cavity, so that the air in the blade cavities will be under a certain amount of pressure. This is necessary in order to provide a sufficient velocity to the fluid emerging from the holes 7.

35 Fig. 4 illustrates the action of my propeller. The blade 5 (shown in section) moves in direction of an arrow 11 under action of the motor (the movement of rotation, the movement of translation being indicated with an arrow 12. An undesirable

vacuum 13 is formed at the rear of the blade, tending to retard the forward movement of the propeller. This vacuum is filled, however, with streams 14 of the fluid under pressure. This fluid in case of an airplane is air and for boats—water.

40 The formation of this vacuum depends to a large extent on the velocity of the movement of translation, and with my arrangement this velocity also increases the fluid pressure in the blades and, consequently, the velocity of the fluid streams 14. This action is entirely automatic, more fluid being admitted to the rear of the blades when more vacuum is formed.

45 It is possible, of course, to assist this action by introducing additional fluid in the blades by means of a suitable apparatus, such as a blower, pump or engine exhaust.

50 With ordinary propellers it is necessary to provide the hub with a sharp pointed cap in order to reduce the air (or water) resistance. With my propeller this is not necessary, as the whole front portion of the hub which contains the cavity, practically does not offer any resistance to the translatory movement, the fluid passing freely inside.

55 I claim as my invention:

60 In a propeller, the combination with a cylindrical hub, of means to mount said hub on a shaft, an outer cylinder concentric with said hub and attached to said hub in the rear, forming a circular clearance in front of said hub, blades attached to said outer cylinder and provided with hollow passages inside in a communication with said circular 65 clearance, a partition in said clearance separating said hub and said outer cylinder separating said clearance for said blades, and spiral guiding surfaces in said partitions extending from the front end of said hub to the 70 inside of said hollow blades and forming smooth passages for air from the front of said hub to the inside of said blades, said blades being provided with a plurality of small apertures in a communication with 75 the inside of said blades and extending through the full length of said blades on one side.

80 Signed at Hempstead, in the county of Nassau and State of New York this seventh 85 day of February A. D. 1927.

JOHN S. BANKRAT.
